UNITED STATES PATENT OFFICE.

EDWARD WILLIAMS, OF NEW YORK, ASSIGNOR TO SUSAN T. WILLIAMS, OF BROOKLYN, N. Y.

SAFETY-PIN.

SPECIFICATION forming part of Letters Patent No. 254,445, dated February 28, 1882.

Application filed September 15, 1881. (No model.)

To all whom it may concern:

Be it known that I, EDWARD WILLIAMS, of New York city, in the county of New York and State of New York, have invented certain Improvements in Safety-Pins, of which the following is a specification.

This invention relates to improvements in safety-pins; and it consists in having attached to a cylindrical or any other form of tube, at one end thereof, a fixed sharp-pointed pin and a corresponding sharp-pointed pin at the other end operated by a spiral within the tube, all of which will be hereinafter more fully described, and set forth in the claim.

15 Figure 1 is a view of a safety-pin, usual size for holding the stocking to the lower part of the drawers. Fig. 2 is an enlarged longitudinal section and transverse section. Fig. 3 shows the application as stocking-supporter.

20 A is the stock or tube, which may be made of any convenient cross-section, either flat and rectangular, oval, or circular, and of any sheet metal, which may be very thin and corrugated, as seen in cross-section, Fig. 2, to give strength thereto transversely. It may also be ornamented. It can be applied for fastening the stockings to the leg of the drawers, also as

a shawl-pin, or in any other manner suitable. The pin B at one end is fixed to the stock A in any convenient manner. The other pin, B', is 30 so bent that the blunt end will enter the tube A within a coiled spring, C, and its shoulder will bear against the outer end of the spring, so that the spring will force the pin outwardly, as shown in Fig. 2.

To use this pin it is only requisite to force the movable point B' into the article and then recoil it and let the other point, B, enter the article, and then the tension of the spring C will force the point B into the article in the 40 opposite direction.

I claim—

A safety-pin formed of a tube having at one end a fixed pin-point, and within the tube, at the other end, a movable bent wire surrounded 45 by a coiled spring, with a pin-point projecting from the wire and operating through a slot in the side of the tube, substantially as and for the purpose described.

EDWARD WILLIAMS.
